CLAIM

The ornamental design for the air freshener, as shown and described.

DESCRIPTION

1. Air freshener

FIG. 1.1 is a perspective view of an air freshener showing my new design;

FIG. 1.2 is a front elevation view thereof;

FIG. 1.3 is a rear elevation view thereof;

FIG. 1.4 is a right side elevation view thereof;

FIG. 1.5 is a left side elevation view thereof;

FIG. 1.6 is a top plan view thereof; and

FIG. 1.7 is a bottom plan view thereof.

The broken lines shown are for the purpose of illustrating portions of the air fresheners and form no part of the claimed designs, and wherein; fig. 1.1 is a top perspective view of the device according to a first design; fig. 1.2 to fig. 1.7 are respectively a front, rear, right lateral, left lateral, top and bottom views of the design of fig. 1.1.
